UNITED STATES PATENT OFFICE.

ADOLF RESOW, OF ESSEN, GERMANY, ASSIGNOR TO FRIED. KRUPP, OF SAME PLACE.

CARRIAGE FOR FIELD-GUNS.

SPECIFICATION forming part of Letters Patent No. 633,867, dated September 19, 1899.

Application filed July 18, 1899. Serial No. 724,244. (No model.)

To all whom it may concern:

Be it known that I, ADOLF RESOW, engineer, residing at Essen-on-the-Ruhr, Germany, have invented certain new and useful Improvements in Carriages for High-Fire Field-Guns, of which the following is a specification.

This invention has reference to improvements in carriages for high-fire field-guns described and claimed in United States Patent No. 620,802, granted to myself and O. Lau-
5 ber March 7, 1899, its object being to reduce the vertical component of the force due to the recoil in such a manner that bracing of the carriage against the ground may be dispensed with or that a comparatively weak extra support will be sufficient. This is accomplished by the use of fluid-brakes interposed between the carriage-stock and the axis of the wheels, respectively the arms or cranks extending
15 from the axles, so as to transmit thereto the relative motion of these parts.

The nature of the invention will best be understood by reference to the annexed drawings, in which—

25 Figure 1 represents a side elevation, partly in section, of a gun-carriage embodying the invention in the position of rest. Fig. 2 is a similar elevation showing the carriage-stock in its lowest position.

30 Similar letters of reference designate corresponding parts in the two views.

As shown in the drawings, the wheel-axle is cranked and consists of a middle part *m*, to which the carriage-stock *l* is pivotally connected, and two cranks *n*, on which the wheels are mounted. Each crank *n* is provided with
35 two eyes *a* and *c*.

40 *b* is a spring-bolt guided within a block *d*, pivoted to the carriage-stock and within the slotted flange *g* of the carriage-stock, its upper end being pivoted to the eye *a* of the crank *n*.

45 Each spring-bolt *b* is provided with a dish-spring column abutting at one end against a nut *e*, screwed onto the bolt, and at the other end against a slotted flange *g* of the carriage-stock.

h designates the piston-rod of a hydraulic brake of the usual construction, with contracted passages for the liquid between the two sides of the piston during recoil, but substantially free communication in opposite direction. The cylinder *i* of the liquid-brake is pivoted to the carriage-stock. The piston-rod *h* is pivoted to the eye *c* of the crank *n*.

The action of the apparatus is as follows: 55 In firing the relative motion of the carriage-stock *l* and of the crank-arms *n* not only compresses the springs *f*, as in Patent No. 620,802, but in addition to this actuates the piston of the liquid-brake. By these means part of the 60 energy of the recoil is taken up in compressing the springs and another part by the resistance of the liquid-brakes. In proportion to the magnitude of the latter part of the recoil the strain on the support is reduced, so 65 that the dimensions of the support may consequently be reduced or the extra support may eventually be omitted altogether.

What is claimed as new is—

In carriages for field-guns, a carriage-stock 70 pivoted to the wheel-axle eccentrically to the axis of the wheels, so as to allow a limited oscillation of the carriage-stock around the axis of the wheels under the action of the weight and recoil; springs between the axles 75 of the wheels and the carriage-stock acting in opposition to the tendency of the weight and recoil to turn the carriage-stock around the axis of the wheels, and liquid-brakes, likewise interposed between the axles of the 80 wheels and the carriage-stock, to take up part of the energy of the recoil, substantially as and for the purpose specified.

In testimony whereof I have hereunto set my hand in the presence of two subscribing 85 witnesses.

ADOLF RESOW.

Witnesses:

WILLIAM ESSENWEIN,
GEO. P. PETTIT.
